OTHER PUBLICATIONS

Co-pending U.S. Appl. No. 29/589,150, filed Dec. 28, 2016, by Janes et al. for "Package."

Primary Examiner — Vy N Koenig(74) *Attorney, Agent, or Firm* — Kimberly-Clark Worldwide, Inc.(57) **CLAIM**

The ornamental design for a package, as shown and described.

DESCRIPTION

FIG. 1 is a perspective view of a package;

FIG. 2 is a front view of the package of FIG. 1;

FIG. 3 is a back view of the package of FIG. 1;

FIG. 4 is a first side view of the package of FIG. 1;

FIG. 5 is a second side view of the package of FIG. 1;

FIG. 6 is a top view of the package of FIG. 1; and,

FIG. 7 is a bottom view of the package of FIG. 1.

In the drawings, the evenly spaced broken lines represent environmental structure and form no part of the claimed design.

1 Claim, 5 Drawing Sheets(56)
